UNITED STATES PATENT OFFICE.

JAMES F. ARTHUR, OF DICKSON CITY, PENNSYLVANIA.

DOMESTIC-BOILER STAND.

1,312,719.

Specification of Letters Patent.

Patented Aug. 12, 1919.

Application filed September 16, 1916, Serial No. 120,541. Renewed January 10, 1919. Serial No. 270,582.

To all whom it may concern:

Be it known that I, JAMES F. ARTHUR, a citizen of the United States, and a resident of Dickson City, in the county of Lackawanna and State of Pennsylvania, have invented a new and Improved Domestic-Boiler Stand, of which the following is a full, clear, and exact description.

Among the principal objects which the 10 present invention has in view are: to provide a stand of the character mentioned which may be adjusted to vary the height of the same to accommodate the plumbing of different installations; to provide a stand 15 adapted for holding boilers of different makes; and to provide neatness of structure to the installation and strengthen the same.

Drawings.

20 Figure 1 is a side elevation of a domestic boiler mounted on a stand constructed and arranged in accordance with the present invention;

25 Fig. 2 is a horizontal section taken as on the line 2—2 in Fig. 3;

Fig. 3 is a vertical section showing a fragment of a boiler and a stand therefor constructed and arranged in accordance with the present invention, the view being shown 30 on an enlarged scale;

Fig. 4 is a detail view showing in sectional elevation a modified form of the invention and a fragment of a boiler supported thereon.

Description.

Heretofore stands of the character mentioned above have been preferably cast as a unit article, and have been made in various 40 sizes to provide a seating collar to receive the lower edge of boilers. Difficulties have been experienced in using these stands arising from the fact that the installed plumbing has often varied as to height and location, compelling the plumber when installing the boiler to adjust his fitting or to raise the boiler and stand by an expedient such as placing under the foot and base of the stand, a block of wood or other material. 45 Even when this expedient has been accomplished, the installation has required in the majority of cases, that the pipes either leading to or from the boiler should be strained or bent. Oftentimes this has occasioned 50 leakage in the couplings of the pipes leading to and from the boiler, or in the water

back of the range with which the boiler is connected. A further objection has arisen in that the variation in the size of the boilers has required a corresponding variation in 60 the diameter of the holding ring for the boilers.

The above objections are obviated by the present invention, wherein a base, such as indicated by the numeral 9, has a central 65 boss adapted to receive the threaded end 10 of a pipe standard 11. A similarly threaded section 12 is provided at the opposite extremity of the standard 11, to engage a threaded collar 13. The collar 13 has a base 70 flange 14 to form a seat rest for the ends of the foot extensions 15 of bow sections 16. The sections 16 are rigidly held on the collar 13 by rivets or bolts 17. At the upper ends of the several bow sections 16, they are 75 connected rigidly with a ring 18, which ring is angular or channel shaped in cross section as shown in Fig. 3 of the drawings. The ring 18, sections 16, and collar 13 are thus united to form a basket support for boilers such as indicated by the numeral 19.

Boilers of this character are conventionally supplied with outwardly-bulged bottoms 20. The bottom 20 of any boiler will set within the ring 18. Therefore, one size 80 of the ring 18 made to the smallest size boiler will answer for all or almost all of the boilers employed for the purpose mentioned. Hence with a stand constructed and arranged as described, the plumber is assured 90 that the stand which he sends from his shop will accommodate the boiler on the job.

The plumber is also able when provided with a stand constructed as described, to 95 adjust the height thereof to insure the disposition of the boiler 19 properly with reference to the installed plumbing with which the same is to be connected. This is accomplished by revolving the standard 11, to the end that the operation of the standard may 100 elevate and depress the collar 13. The threads on the ends 10 and 11 of the said standard are relatively right and left pitch, consequently, when the standard is revolved, the collar 13 is lifted from or lowered to 105 toward the base 9.

Boilers of the character mentioned are usually provided with a delivery pipe 21. This is connected by a T-coupling 22, with the boiler. At the outside of the T-coupling 110 22, a drain pipe 24 is provided having a draw-off faucet 28.

2
In the modified form of the invention as shown in Fig. 4 of the drawings, the T-coupling 22 is installed with the opposite outlets in vertical arrangement rather than as shown in Fig. 3 of the drawings in conventional horizontal arrangement. In the modified form, the standard 11 covers a portion of the delivery pipe which passes downward therethrough. The valve 25 is mounted on the pipe 26. A drain pipe 28 conducts water from the pipe 26 to any convenient waste.

Claims.

15. 1. An apparatus as characterized comprising a base having a central orifice; a basket-like member having an annular ring for forming a receptacle for a boiler and having a central orifice; and means connecting said base and said receptacle, said means em-

bodying a standard having right and left screw threads to engage corresponding threads in said orifices for elevating said receptacle relatively to said base.

2. An apparatus as characterized comprising a base having a central screw-threaded orifice; a basket-like member having an annular ring for forming a receptacle for a boiler and having a central screw-threaded orifice; and means connecting said base and said receptacle, said means being adapted for elevating said receptacle relatively to said base, said means embodying a hollow open-ended standard having screw threads for engaging corresponding threads in said orifices.

JAMES F. ARTHUR.
